[57] CLAIM

The ornamental design for an ornament for table or other supporting surface, substantially as shown and described.

DESCRIPTION

FIG. 1 is a front perspective view of an ornament for table or other supporting surface showing our new design;

FIG. 2 is a rear perspective view thereof;

FIG. 3 is a side elevation thereof; and

FIG. 4 is an elevation of the other side thereof.

The bottom of the ornament is plain.

FIG. 1.

FIG. 2.

FIG. 3.

FIG. 4.
